CLAIM

The ornamental design for the airline telephone handset, with digital passenger control functions and video game controls, as shown and described.

DESCRIPTION

FIG. 1 is a first end view of an airline telephone handset with digital passenger control functions and video game controls showing my new design;

FIG. 2 is a second end view of that illustrated in FIG. 1; FIG. 3 is a bottom plan view of that illustrated in FIG. 1; FIG. 4 is a top plan view of that illustrated in FIG. 1; FIG. 5 is a left elevation view of that illustrated in FIG. 1; and,

FIG. 6 is a right elevation view of that illustrated in FIG. 1. The broken line disclosure throughout the views is for illustrative purposes only and forms no part of the claimed design.
